Herbert E. Smith

UNITED STATES PATENT OFFICE.

BERNARD V. APFELD, OF SPOKANE, WASHINGTON.

WRENCH.

1,375,071.

Specification of Letters Patent. Patented Apr. 19, 1921.

Application filed August 10, 1920. Serial No. 402,610.

To all whom it may concern:

Be it known that I, BERNARD V. APFELD, a citizen of the United States, residing at Spokane, in Spokane county and State of Washington, have invented certain new and useful Improvements in Wrenches, of which the following is a specification.

My present invention relates to improvements in wrenches of the sliding jaw, cam closure type, well adapted for the functions of a tool of this character and as a pipe wrench. The tool of the invention is also capable of use as a vise, and may with facility and convenience be converted for use as a rotary, hand operated brace for boring tools, screw drivers, and for other purposes.

With the above ends in view the invention consists in certain novel combinations and arrangements of parts involving a pair of parallel jaws, one of which is movable, with means utilizing a cam or incline device for operating the movable jaw toward or away from the fixed jaw to secure various adjustments.

In the accompanying drawings I have illustrated one complete example of the physical embodiment of my invention in which the parts are combined and arranged according to the best mode I have thus far devised for the practical application of the principles of my invention.

Figure 1 is a view in elevation illustrating a wrench constructed according to and embodying my invention, a crank handle being shown in dotted lines to indicate the use of the tool as a brace for rotary boring.

Fig. 2 is a view at the rear edge of the tool, part broken away.

Fig. 3 is a detail perspective view of the movable jaw and its cam block or arm and connections.

Fig. 4 is a sectional detail view showing the relation of the slide sleeve to the tool shank and the locking ratchet plate between the sleeve and shank.

Fig. 5 is a detail view showing a plan of the cam block and cam shoe, the pivotal support for the shoe being shown in section.

In the preferred form of the invention as illustrated in the drawings I utilize a shank 1 of usual or approved form which is equipped with the hand grasp or handle 2, usually of wood and secured thereon in approved manner. The shank is fashioned with an offset, integral, fixed jaw 3 having

its operating face slightly offset from the axial line of the shank, and along the rear or back edge of the shank, below the jaw are provided a pair of side or lateral rows of rack teeth 4, 4, and an intermediate row of teeth 5 disposed in direction opposite to the direction of the outer or lateral rows of teeth 4, 4.

At the sides of the fixed jaw, adjacent the shank, are provided mortises for the reception of the side plates 6, 6, of a metallic frame which is secured by screws 6' and extends or projects laterally from the jaw. The frame of which the plates 6 form a part, is fashioned with two pairs of slots 7, 7, one pair in each plate, aligned, and disposed perpendicular to the face of the fixed jaw 3.

Within the lateral frame, the movable or slide jaw 8 is adapted to operate, and the pairs of side lugs 9, 9, integral with the movable jaw are guided in the slots of the side plates in order that the movable jaw may remain at all times parallel with the fixed jaw and travel toward or away from the latter with a stable movement.

The jaw 8 is moved laterally of the fixed jaw through the instrumentality of the longitudinally movable or slidable cam block 85 10, which is fashioned in such form as to project obliquely from the shank 1 against which it bears at one or its inner end, and the block is slotted as at 11 substantially throughout its length, the slot being also inclined to the axial line of the tool or its shank. At its outer end the block is provided with lateral lugs 12 and grooves 12' to guide it in its movement in the frame between the side plates 6, 6, for it will be apparent that the block is slid longitudinally of the shank with its outer or projected end incased in and guided by the plates of the frame. A flexible connection is provided between the laterally movable jaw and the longitudinally movable block by the fixed lug 13 on the jaw which bends downwardly, and terminates in a pivot pin 14, and on the pin a shoe 15 is pivoted or loosely journaled. The shoe is complementary to 100 and slides with a neat fit in the slot 11 of the cam block, and the pin extends transversely through the slot. Thus, as the block is slid along the shank, it will be apparent that through the flexible connection and the 105 cam slot in the cam block, the movable jaw will be moved toward or away from the

fixed jaw, for clamping or releasing an object between the two jaws.

This movement of the jaw 8 is effected through the actuating slide sleeve 16 surrounding the shank and slidable thereon. The sleeve is of metal, with a rectangular interior to move smoothly along on the shank, and is fashioned with a closed, integral yoke 17 through which a screw 18 is freely passed and disposed parallel with the shank. The end of this screw, at 19 is threaded into the cam block, and a lock nut 20 is used to clamp the screw or bolt in the block. Within the yoke and on the screw is located a non-traveling nut 21 which may be utilized, by turning on the screw within the yoke, for moving the cam block and jaw 8 when the device is to be used as a vise.

When using the tool as a wrench, however, the slide sleeve, its yoke and the screw are bodily moved to actuate the slide or cam block, for moving the jaw 8. The sleeve is secured in adjusted position on the shank by means of the spring pressed rack plate 22, which is provided with two pairs of side arms 23 movable in grooves 23' on the outer side surfaces of the sleeve, and heads 24 on these arms are retained in the recesses 25 in the sides of the sleeve at the terminals of the grooves 23', to limit the movement of the rack plate. The sleeve is slotted in order that teeth 26 and 26' on the rack plate may engage the complementary teeth 4 and 5 on the shank, which it will be remembered are disposed in opposed directions, and a plate spring 27 on the sleeve is utilized to retain the plate in contact with these teeth. By the utilization of the opposed sets of teeth and the spring, the rack plate is held rigidly on the shank and the sleeve cannot be moved in either direction while the rack plate is in closed position. Thumb pressure on the rack plate, against the spring, however, will release the plate and the sleeve may then be slid along the shank to force the movable jaw toward its fixed jaw, or to separate the movable jaw from the fixed jaw.

For converting the tool for use as a boring tool I use a squared collar 28 on the squared portion 29 of the threaded shank end, over which the socket head 30 of the crank arm 31 fits, and by means of the handle 32 the tool may be revolved as a brace for a boring tool. The nut 33 on the end of the shank stem is of usual construction and function.

Thus the wrench may be used either for its customary function, or as a pipe wrench, and the tool, through the operation of the

non-traveling nut 21 may be used as a vise; and with a bit or screw driver clamped between the jaws of the tool, the whole device may be revolved by means of the handle 31-32 as a brace or screw driver.

From the above description taken in connection with my drawings it is apparent that I have provided a device which is comparatively simple in construction and operation, is compact and durable, and may be utilized for various purposes to which similar tools are adapted.

Having thus described my invention, what I claim as new and desire to secure by Letters Patent is—

1. The combination with a fixed jaw and its laterally projecting guide frame, of a parallel jaw movable in said frame, a longitudinally movable block guided in the frame and having a cam slot therein, a pivoted shoe on the movable jaw slidable in said slot, and means for moving said block, for the purpose described. 75

2. The combination with a fixed jaw and its laterally projecting slotted frame, of a movable jaw having lugs guided in the slotted frame, a longitudinally movable block guided in the frame and provided with a cam slot, a pivoted shoe on the movable jaw guided in said cam slot, and means for moving said block for the purpose described. 85

3. The combination in a wrench with its fixed jaw and shank and a laterally projected frame on the jaw, of a bodily movable jaw guided in the frame, a longitudinally movable cam member guided in the frame 95 and flexibly connected with said movable jaw, a slide sleeve on the shank rigidly connected to said cam member, co-acting rack teeth on the shank and a rack plate on the sleeve, and means for holding said rack 100 plate and shank in locked position, as described.

4. The combination in a wrench with its fixed jaw and toothed shank, a laterally projected slotted frame on the jaw, and a movable jaw in the frame having lugs as described, of a longitudinally movable cam member having an obliquely extending slot and guided in said frame, a loose shoe on the movable jaw guided in said obliquely 110 extending slot, an open end sleeve movable on the shank and connected to said cam member, a toothed rack plate having arms connected with said sleeve, and a spring on the sleeve holding said plate in adjusted 115 position.

In testimony whereof I affix my signature.
BERNARD V. APFELD.
